WIRE SPACING DEVICE

John C. Steadman, Jacobsburg, Ohio, assignor to
Lyda D. Curtis, McMechen, W. Va.

Application June 22, 1953, Serial No. 25,606

Term of patent 7 years

(Cl. D26—10)

To all whom it may concern:

Be it known that I, John C. Steadman, a citizen of the United States, residing at Jacobsburg, in the county of Belmont and State of Ohio, have invented a new, original, and ornamental Design for a Wire Spacing Device, of which the following is a specification, reference being had to the accompanying drawing, forming part thereof.

Figure 1 is a top plan view of a wire spacing device, showing my new design;

Figure 2 is a side elevational view thereof;

Figure 3 is an end elevational view as it appears from the left side of Figure 1;

Figure 4 is an end elevational view as it appears from the right side of Figure 1; and

Figure 5 is a cross-sectional view of the same, taken on the line 5—5 of Figure 1, looking in the direction of the arrows.

I claim:

The ornamental design for a wire spacing device, as shown.

JOHN C. STEADMAN.
